UNITED STATES PATENT OFFICE.

CHARLES A. BAECHTOLD, OF MOUNTAINSIDE, NEW JERSEY, ASSIGNOR TO LIDGERWOOD MANUFACTURING COMPANY, OF NEW YORK, N. Y., A CORPORATION OF NEW YORK.

CAR-TRANSFERRING MEAN.

1,013,106.

Specification of Letters Patent.

Patented Jan. 2, 1912.

Application filed October 3, 1911. Serial No. 652,482.

To all whom it may concern:

Be it known that I, CHARLES A. BAECHTOLD, a citizen of the United States, residing at Mountainside, in the county of Union and 5 State of New Jersey, have invented certain new and useful Improvements in Car-Transferring Means, of which the following is a specification.

My invention relates to new and useful 10 improvements in car transferring means, and more particularly contemplates power-operated means for use in mines to transfer the cars which are employed to carry out the diggings of the mine.

15 The invention consists in the improvements to be fully described hereinafter and the novelty of which will be particularly pointed out and distinctly claimed.

20 I have fully and clearly illustrated my invention in the accompanying drawings to be taken as a part of this specification and wherein:

25 Figure 1 is a section through a mine showing in plan an embodiment of my invention; Fig. 2 is an enlarged plan view of an embodiment of my invention; Fig. 3 is a view in side elevation; and Fig. 4 is a detail sectional view of a clutch operating means employed.

30 According to present mining practice, when cars are employed for carrying out the diggings, the cars are transferred or propelled through the main headings and galleries of the mines by cable systems, electric 35 trolley systems, and draft mules, and the cars are transferred or switched into the branch headings or rooms by mules in each of the cases mentioned, as it is impracticable to extend the cableway systems or electric 40 systems into the branch headings, so that, no matter what form of power is employed for propelling the cars through the main headings or galleries, mules have formed the draft means for propelling the cars into the 45 branch galleries where the mining operations are taking place.

By my invention according to the embodiment to be described a portable power plant is employed adapted to travel on the track 50 of the main heading, and a plurality of draft lines, one for each branch heading, and an individual operating drum for each line located at the entrance to each branch head-

ing, provision being made whereby the portable power plant may be coupled individually to the drums to pull the cars into the respective headings.

Referring to the drawings by characters of reference: 1 designates the main heading or gallery of a mine, and 2, 2 are the branch 60 headings or rooms in which the mining operations are being performed, the latter being separated by partitions 3 as shown.

Extending longitudinally of the main gallery 1 is the main trackway 4 upon which 65 the cars are propelled to and from the branch headings, said trackway being joined to a branch trackway or siding 5 which enters and extends longitudinally of the branch heading, and 6 is a car to travel 70 on the main and branch trackways. It will be understood that there will be a branch trackway for each branch heading or for each heading which is being mined. At the entrance preferably of each branch heading is arranged a winding drum 7 mounted on a horizontal shaft 8 in bearings 9 on a frame 10. The drum is provided with a brake rim 11 with which coöperates a brake shoe 12, see Fig. 3, mounted on one end of an 80 intermediately fulcrumed lever 13 on the opposite end of which is a weight 14 normally swinging the lever to urge the brake shoe into engagement with the brake rim so that the drum may revolve under friction. The 85 head of the drum is also provided with a beveled gear 15 with which meshes a gear 16 on the end of a shaft 17 extending at right angles to the longitudinal axis of the drum and journaled in a bearing 18 on the 90 main frame. At its end opposite to that carrying the gear 16 the shaft 17 carries one member 19 of a universal joint of well known form and having the arms 20.

Wound upon the drum just described is a 95 cable 21 which extends lengthwise of the branch track in the heading and is passed over snatch blocks or other forms of rope guides 21^a in the end of the heading and then carried central of the track so that it may 100 be conveniently secured by any suitable means to a car 22. By this arrangement it will be seen that the line may be attached to a car and upon revolving the drum to wind up the rope, the car will be drawn up 105 into the branch heading to the point desired.

by the miner. It will be understood that there is one of these drums and its cable in each branch heading which is being mined and that the same may be readily set up and taken down as the progress of the mining takes place from one branch heading to another.

I will now describe the means whereby any one of the drums employed may be driven individually by power to draw a car into a heading. This means consists of a portable power plant adapted to travel on the main trackway in the main heading, the same being in the form of a car 23 having running wheels 24 to travel on the main trackway. Mounted on this car is a motor 25 the shaft of which carries a gear pinion 26 meshing with a gear 26^a on a shaft 27, the latter carrying a pinion 28 in mesh with a gear 29 loosely mounted on a power shaft 30. This gear 29 also meshes with a gear 31 loosely mounted on the axle 32 carrying one set of the running wheels. Slidably mounted on the power shaft and keyed thereto is a clutch member 33 adapted to be moved longitudinally of said shaft to coöperate with a clutch 34 on the gear 29 to couple the latter to the power shaft whereby the latter is driven. There is also a clutch member 35 keyed to the axle 32 and adapted to be moved longitudinally thereof to couple said axle and the gear 31.

36 designates a horizontally disposed clutch-operating shaft, journaled in bearings 37 on the car frame and having oppositely projecting yokes 38, 39, adapted to engage respectively with the clutch members 33, 35, the arrangement being such that the rotation of the operating shaft 36 serves to operate the clutches 33, 35 in opposite directions; that is, when rotated in one direction, it throws the clutch 33 in and the clutch 35 out, while, when rotated in the opposite direction, the clutch 33 is thrown out and the clutch 35 in. It will thus be seen that, when the power shaft clutch is in, the driving wheels are disconnected from the motor, and that, when the driving wheel clutch is in, the power shaft is stationary. 60 A suitable hand lever 40 is provided for operating the clutch shaft.

The operator's station or platform is shown at 41 adjacent to which is a current controller 42, and a hand lever 43 on a brake shaft 44, carrying brake shoes engaging the running wheels. The current for the motor is collected from trolley wires (not shown) by a trolley 45 in a well-known manner. It is not thought necessary to illustrate the circuits for the motor, as they form no part of my invention.

Connected by a universal joint 46 with the outer end of the power shaft 30 is tubular shaft member 47 having an angularly walled interior to receive the angularly faced por-

tion 48 of a shaft member 49 carrying on its outer end the complementary member or part 50 of a universal joint of which the parts 19, 20, heretofore described, form the other member. This universal joint may be as shown in the form of the well known Hooke Gimbal joint, and I make the parts readily detachable so that the power shaft of the power plant may be easily coupled and uncoupled from any one of the drums associated with the branch headings. In order to accomplish this, I make the pin 51 for connecting the center piece 52 to the arms 20 removable, and connect it by a flexible connection 53 with the shaft 49 so as to prevent loss.

When the invention is to be installed and operated it will be understood that one of the drums 7 is located adjacent the entrance of each branch heading which is intended to be mined or which is being mined, and the blocks 21^a are suitably fixed at the inner end of the heading, the cable mounted on the drum being passed over the blocks as heretofore described. As the empty cars enter the mine and are propelled along the main heading, whenever the progress of the winding operation requires that one of these cars be drawn into one of the branch headings, the car is shoved from the main trackway onto the branch trackway after which the free end of the cable 21 is attached thereto. The portable power plant, if it is not already adjacent the heading into which the car is to be drawn, is propelled by its own motor to a point adjacent the heading, as shown in Figs. 1 and 2, the clutch 35 being in engagement with the gear 31 on the axle, and the clutch 33 being disengaged from the gear 29 on the power shaft during the movement of said power plant. When the power plant arrives at the point where it is to operate, the clutches are shifted so that the running gear is disconnected from the motor and the clutch 33 is placed in engagement with the clutch element on the gear 29 so that the shaft composed of the parts 47 and 49 may be driven. The part 52 of the universal joint heretofore described is then coupled to the parts 20 of the part 19 by means of the pin 51. The operator then, by means of his controller, throws the current onto the motor to drive the power shaft which, through the intermediate gear, operates said shaft to rotate the shaft composed of the parts 47 and 49 to revolve the drum 7 and thereby wind the cable 21 thereon whereby the empty car is drawn into the branch heading, this operation continuing until the car reaches the point desired. The shaft for connecting the power plant and the drum may then be disconnected from the drum and the power plant may be moved along the main heading in order that it may be connected to any one of the other

drums which may be desired. The brake 12, operating on the friction surface 11 on the drum 7, operates to hold the drum so that the car will be held at any point to which it may be drawn. When the car is to be taken from the branch heading, it may be disconnected from the line 21 and permitted to pass from the heading by gravity, or, if desired, the cable may remain connected there-
10 to and the car pass from the heading by gravity under control of said brake 12.

It will be seen that the construction of the shaft 47, 49 permits its length to be varied so that it may be properly and conveniently connected to any one of the drums 7 without the necessity of placing the same at any fixed distance from the main trackway. When the power plant moves along the main heading it will be understood that
20 the drum driving shaft may be folded back on the universal joint 46 and supported on the car 23 in any suitable manner to have it clear obstructions and prevent it from dragging on the floor of the mine.

25 While I have described this invention as a means for transferring the cars in a mine, it will be understood that it is not necessarily limited to use in connection with mining operations, but may be employed in connection with any system of transportation which involves the main trackway from which extend branch trackways or any system of transportation in which there is a main trackway and one or more trackways
30 extending at an angle to the main trackway.

35 While I have shown and described what appears to me at the present time to be the best embodiment of my invention, I do not wish to be limited to the particular construction and arrangement of parts as they are capable of wide variation without departing from the spirit and scope of the invention, more particularly the construction of the power plant and the means for connecting the same to the windlass or other cable-operating means, or the specific structure of the cable-operating means. For instance, the power plant need not be provided with self-propelling means, but could
40 be otherwise moved to the point where it is to operate and the power plant could be connected to the cable-operating means by any power transmitting arrangement which could be readily coupled and uncoupled
45 therefrom.

50 I do not employ the term "fixed" in the claims in a limiting sense as designating any way in which the rope-operating drums are mounted at the branch trackways.

55 What I claim and desire to secure by Letters Patent of the United States is:—

1. In a system of the character described, the combination of a main trackway, a trackway at an angle thereto, a winding
60 drum fixed at said angularly disposed track-

way, a cable operated by said drum, a portable power plant adapted to travel on the main trackway, and means for connecting the portable power plant to the said fixed drum to drive the latter.

70

2. In a system of the character described, the combination of a main trackway, a plurality of trackways at an angle thereto, a winding drum fixed at each of said angularly disposed trackways, a cable operated by each of said drums, a portable power plant adapted to travel on the main trackway, and means for connecting the portable power plant with said fixed drums to drive the latter.

75

3. In a system of the character described, the combination of a main trackway, a plurality of branch trackways connected to the main trackway at an angle thereto, a winding drum fixed at each of said angularly disposed trackways, a cable operated by each of said drums, a portable power plant adapted to travel on the main trackway, and means for connecting the portable power plant with said fixed drums to drive the latter.

80

4. In a system of the character described, the combination of a main trackway, a plurality of trackways at an angle thereto, a winding drum fixed at each of said angularly disposed trackways, a cable operated by each of said drums, a portable power plant adapted to travel on the main trackway, a shaft connected to the power plant by a universal joint, and means for connecting the shaft to the fixed drums.

85

5. In a system of the character described, the combination of a main trackway, a plurality of trackways at an angle thereto, a winding drum fixed at each of said angularly disposed trackways, a cable operated by each of said drums, a portable power plant adapted to travel on the main trackway, a shaft connected to the power plant by a universal joint, and a detachable universal joint for connecting said shaft with said fixed drums.

90

6. In a system of the character described, the combination of a main trackway, a plurality of trackways at an angle thereto, a winding drum fixed at each of said angularly disposed trackways, a cable operated by each of said drums, a portable power plant adapted to travel on the main trackway, and an extensible, universal connection for connecting the power plant to said fixed drums.

95

7. In a system of the character described, the combination of a main trackway, a plurality of trackways at an angle thereto, a drum fixed at each of said last-mentioned trackways, a portable power plant on the main trackway, a propelling shaft and a power shaft on the power plant, a motor, means for coupling the motor to either of

100

105

110

115

120

125

130

said shafts, and means for connecting the power shaft to said fixed drums to drive the same individually.

8. In a system of the character described, 5 the combination of a main trackway, a plurality of trackways at an angle thereto, a drum fixed at each of said last-mentioned trackways, a cable wound on each drum and extending longitudinally of the trackway 10 and over guides at a point remote from said drums, a portable power plant on the

main trackway, and means for connecting the power plant to any one of said fixed drums whereby the latter is driven.

In testimony whereof I have hereunto 15 signed my name in the presence of two subscribing witnesses.

CHARLES A. BAECHTOLD.
